UNITED STATES PATENT OFFICE

HENRY L. DOHERTY, OF NEW YORK, N. Y., ASSIGNOR TO DOHERTY RESEARCH COMPANY, OF NEW YORK, N. Y., A CORPORATION OF DELAWARE

CRACKING HYDROCARBON OILS

Original application filed February 24, 1920, Serial No. 361,030. Divided and this application filed October 1, 1931. Serial No. 566,263.

This invention relates to a process of distilling oil and more particularly to a process for cracking heavy hydrocarbon oils to form lighter hydrocarbon oils therefrom.

5 This application is a division of pending application Serial No. 361,030, filed February 24, 1920, for "Process of distilling oils".

Heretofore the commercial processes for cracking heavy hydrocarbon oils to produce 10 lighter hydrocarbon oils, particularly gasoline, have employed a cylinder still in which the oil is heated in a large body. The inherent nature of the cylinder still presents certain 15 limitations in the process which hold down the character and quantity of gasoline which may be recovered. Among these limitations are the formation of hydrocarbons of higher and lower boiling points than the boiling points of the gasoline desired. Although oil 20 may be cracked through a wide range of temperatures, the most advantageous cracking is obtained in a specific narrow range of temperatures. Experience has shown that at the higher temperatures, the rate of reaction is 25 very rapid with a consequent formation of large amounts of fixed gases and carbon. With lower temperatures, the reaction is slower and consequently the time element is an important factor. Since oil is such a poor 30 conductor of heat, it is not practical to use the lower temperatures when distilling oil in a cylinder still and in fact the outside of the still is subjected to very high temperatures in order to drive the heat into the center of the 35 body of oil. This causes a local overheating and a layer of coke is always formed around the inner surface of the still.

One object of the present invention is to 40 provide a process by which oil may be uniformly heated to any desired temperature.

A further object of the invention is to provide a pressure cracking process in which the concentration of tarry materials in the oil in the cracking zone may be effectively controlled.

Accordingly, a feature of the invention 45 comprises the withdrawal of oil residuum from the pressure cracking system through the withdrawal lines, intermittently with a pulsating operation to prevent the stoppage

of these lines due to the deposition of carbon and coke from the oil residuum.

With these and other objects in view, the invention consists in the improved process for cracking oil hereinafter described and 55 claimed.

The various features of the invention are illustrated in the accompanying drawings, in which:

Fig. 1 is a view in side elevation, partly in 60 section, showing a cracking still embodying the preferred form of the invention;

Fig. 2 is a top plan view of the cracking still shown in Fig. 1.

The process of the present invention provides a treatment of heavy or high boiling hydrocarbon oils to produce light or low boiling point oils. The raw material for treatment may be kerosene, gas oil, fuel oil, or a mixture of two or more of these, and the treatment always produces lower boiling point hydrocarbons therefrom. Under the present commercial conditions the treatment is conducted to produce gasoline. In carrying out the process in the apparatus shown 65 in the drawings, the raw oil from storage is drawn in through a pipe 10 to a pump 12 and carried by means of a pipe 14 into the first condenser 16 of a series of surface condensers 16, 18, 20, 22, 24, 26, 28 and 30 (Fig. 2). It 70 then advances through the condensers while being passed in heat-transferring relationship with oil vapors, which are formed in the cracking operation and flow through the surface condensers countercurrent to the flow of 75 oil. The oil is preheated by the vapors at 300-450° F., depending upon the temperature of the vapors, and flows from the condenser 30 through a pipe 34 (Fig. 2), and enters the upper portion of a cracking chamber 36. In 80 the cracking chamber, the oil is formed into a series of bodies which are separated by trays or horizontal partitions 38 and the oil overflows by gravity from one tray to the next tray below through overflow pipes 40. When 85 the oil has flowed downwardly in the cracking chamber to a tray 42 (Fig. 1), it meets a body of oil which is introduced through a pipe 44. The oil introduced through the pipe 44 has been previously treated in the crack-

90

95

100

ing operation and has been heated to the most advantageous cracking temperature. By the time the incoming raw oil reaches the tray 42, its temperature is raised to substantially 5 the cracking temperature by the hot vapors and gas passing therethrough. The mixture of preheated raw oil and the heated oil admitted through the pipe 44 is then held at a cracking temperature as it flows downwardly 10 to the bottom of the cracking chamber to an outlet pipe 46.

The incoming raw oil and the mixture of raw oil and cracked oil which flow downwardly through the cracking chamber are 15 constantly agitated by means of gas and oil vapors which are admitted to the bottom of the still through a pipe 48. To accomplish this, the plates 38 which form the bottom of the trays are preferably provided with per- 20 forations which have such a size that the gas is permitted to pass upwardly therethrough while the oil is prevented from passing downwardly therethrough. In this way, the gas and vapors entering through the pipe 48 pass 25 upwardly through the bodies of oil on the trays to actively agitate the oil and to transfer to the oil any superheat which they may possess. Further, the oil vapors leaving one tray encounter the oil on the tray above and 30 there is always an intermingling of oil and vapor and an interchange of heat between the vapors and oil. This causes a continual change of state from liquid to the higher boiling point vapors and vice versa, which is in- 35 ductive of cracking and increases the percentage of low boiling point products in the vapors leaving the cracking chamber.

A portion of the raw oil entering the body of oil in the cracking chamber is cracked in 40 its passage through the cracking chamber from the tray 42 to the bottom of the cracking chamber. The uncracked portion of the oil, together with any uncracked oil which remains from the oil introduced through the pipe 44, after it passes downwardly through the cracking chamber, flows out through the pipe 46 to a pump 50 which forces it through a pipe 52 to a pipe still 54. As the oil flows through the pipe 52, a gas is introduced into 45 the oil through a pipe 56 by means of a pump 58. The gas flows in contact and in parallel current with the oil and serves to actively agitate and accelerate the velocity of the oil passing through the pipe still 54. Further, 50 the oil vapors which are formed in the pipe still are absorbed by the gas flowing in parallel current therewith and at the time the oil and gas have passed through the coil of the pipe still, they are heated to a cracking tem- 55 perature and the gas is saturated with vapors which are also heated to a cracking tem- perature. The oil leaving the cracking chamber to pass to the pipe still is heated to sub- 60 stantially a cracking temperature and there- fore only a small amount of heat will have to

be supplied in the pipe still to vaporize the oil and to provide for any heat of reaction in cracking the oil.

The mixture of gas, oil and vapors leaving the pipe still flows through a pipe 60 into a separator 62 where the oil is separated from the gas and vapors, and the gas and vapors then flow through a pipe 64 to the pipe 48 positioned at the bottom of the cracking chamber. The oil collected in the separator 62 flows out through a pipe 66 to a float valve 68 and then passes into the pipe 44 connected with the upper portion of the cracking chamber. As described above, the oil introduced through the pipe 44 together with incoming oil flowing downwardly through the upper portion of the cracking chamber are heated to the cracking temperature and pass in a countercurrent path through the gas and vapors which are also heated to a cracking 80 temperature. By the countercurrent movement of the oil and vapors, the oil bodies in the cracking chamber are maintained at substantially a uniform temperature, which temperature can be accurately controlled to be 85 the most desirable temperature for cracking oil in order to give a maximum yield of gasoline. The heated gas passing upwardly through the oil, along with the vapors, acts as an absorbent for the gasoline vapors and 90 helps to sweep them out of the reaction zone and carry them out of the cracking chamber.

As the gas and vapors pass upwardly from the tray 42 through the incoming oil, a certain portion of the higher boiling constituents is condensed in the oil and returned to the cracking zone. The sensible heat of these gases and vapors and the heat of vaporization of the vapors condensed serve to pre- 100 heat the raw incoming oil to a cracking tem- perature. These vapors leaving the upper- most tray of the cracking chamber pass through a reflux condenser 70 mounted on and communicating with the upper portion 105 of the cracking chamber. The temperature of the reflux condenser 70 is regulated by means of water which is introduced through a pipe 72. The introduction of water is controlled by a thermostatic valve 74 which in turn is controlled by a thermostat 76 mounted in the upper portion of the condenser. With the thermostatic control, vapors of any desired boiling point may be condensed and carried back into the cracking chamber so as to permit only vapors having a predeter- 110 mined temperature to pass into the condensers 30—16. Steam produced in condenser 70 may be discharged through a pipe 115 120 125 130 135 140 145 150 155 160

The gas and vapors leaving the reflux con- denser pass through a pipe 78 and enter the last surface condenser 30. These gases and vapors then pass in series through the condensers 30—16 and finally flow out through a pipe 80, (Figs. 1 and 2) to a water-cooled

condenser 82 where the lowest boiling point hydrocarbons are condensed. The fixed gases formed in the process, together with the gases introduced into the circuit through the pipe 56, flow from the condenser through a trap 83 to a pipe 84 by which they are introduced into the lower portion of an oil scrubber 86. In the scrubber 86 the gases are treated with a mineral oil to remove the uncondensed vapors and the gases leaving the upper portion of the scrubber 86 flow through a pipe 88 to the pump 58. Any excess of gas over that necessary in the process may be removed through the pipe 90. If desired, gas from an external source for starting the process or for any other purpose, may be introduced through the pipe 90.

As the mixture of gas and vapors advances through the condensers 30-16, it is gradually cooled by the incoming raw oil advancing through the condensers 16-30. The gradual interchange of heat between the incoming oil and the gas and vapors permits the condensation of fractions with sharply defined boiling points, which may vary only by a few degrees of temperature. This intensified fractionation of vapors permits the recovery of a number of products of substantially the desired boiling points and thus avoids the necessity of several redistillations in recovering the marketable products. The fractions condensed in the condensers 30-16 are removed through outlet pipes 92 (Fig. 1) to look-boxes 94 and flow into traps 96 from which they are conducted through pipes 98 to their respective cooling coils 100. The coils 100 are supported in a water-cooling tank 102 and each coil has a connection 104 by which the condensates may be conducted to their respective collecting tanks. If desired, any or all of the condensates passing through the traps 96 may be returned to the cracking chamber by closing valves 106 in the pipes 98 and opening valves 108 in a run-back line 109, which connects with the raw inlet pipe 34. With the apparatus outlined above, the process may be so conducted that all of the heavy fractions of the oil may be held back by the reflux condenser and the incoming oil in the upper portion of the cracking chamber and only the vapors of the desired oil fractions to be recovered are allowed to pass through the surface condensers 30-16. Also, some of the surface condensers may be used in conjunction with the reflux condenser in carrying back any desired fraction to the cracking chamber. Further, if any of the fractions in the surface condensers do not meet the desired specifications, they may be returned to the cracking chamber through the run-back line 109 for retreatment. To promote the positive circulation of the vapors and gas in the condensers and to maintain the proper pressure conditions throughout the apparatus, a pressure-equal-

izing pipe 110 (Fig. 1) is connected between the vapor-pipe 78 and the oil-inlet pipe 34.

In all cracking processes a certain amount of carbon and tarry sludge is always formed and if this material is not removed from the still or oil circuit, it will soon interfere with the cracking operation. Due to the high velocity with which the oil and gas go through the coil of the pipe still 54, the carbon deposited therein is reduced to a minimum. The principal portion of the carbon and tar is set free in the separator 62. The carbon and tar set free in the separator 62 pass down with the oil through a tube 111 (Fig. 1) to a settling chamber 112 where the oil slowly rises to the top and the carbon and tar settle to the bottom. This carbon and tar is intermittently drawn off from the chamber 112 through a pipe 113 and passes through a valve 114 to a still 116. Since the oil in the settling chamber 112 is heated to a cracking temperature while under a high pressure, it contains a large amount of potential energy or sufficient sensible heat to vaporize approximately 50% of the oil when it is reduced to atmospheric pressure. Accordingly, the still 116 is maintained at atmospheric pressure and the carbon and tarry sludge is intermittently drawn off from the settling chamber 112 by opening up the valve 114. The still 116 is not heated but the sensible heat in the sludge will vaporize the lighter constituents at atmospheric pressure and these vapors will pass out of the still through a pipe 118 to a condenser 120. The vapors collected in the condenser 120 may then be added through the line 121 to the raw oil entering the pump 12 for retreatment in the cracking still.

Since the cracking operation is completed in the cracking chamber 36, considerable carbon and tar sludge will be formed therein. To remove this carbon and tar from the oil circuit, the lower end of the cracking chamber is provided with a conical collecting chamber 122 (Fig. 1), which is connected through a valve 124 and pipe 126 with the still 116. The oil containing carbon and tar may be drawn from the cracking chamber 36 in the same manner that it is withdrawn from the collecting chamber 112 and passed into the still 116 to recover any light oil vapors therefrom. The heavy tar sludge which does not vaporize in the still 116 is withdrawn through an outlet 127. Although the distillation operation is continuous, it is preferred to operate the valves 114 and 124 for withdrawing sludge from the oil circuit alternately and intermittently since an intermittent pulsating operation tends to clear the heavy sludge from the pipes 113 and 126 due to the rapid rush of the high pressure oil into the low pressure still 116.

Of the high boiling point vapors which are formed in an oil cracking operation,

those vapors which condense at temperatures above 400 to 450° F. carry a large amount of carbon and tarry material. If these vapors are condensed in contact with cooling surfaces, this tarry material is deposited and clogs the condensers as well as seriously interfering with the heat transfer of the condenser. With a cracking chamber constructed as described above, this difficulty is overcome since the vapors are cooled to the desired minimum temperature for removing carbon and tarry material by passing them through the incoming oil in the upper portion of the cracking chamber before the heavy vapors come into contact with the cooling surface of the reflux condenser. When the heavy vapors are condensed within the oil, the carbon and tarry material is caught in the oil and carried downwardly to the collecting chamber at the bottom of the cracking chamber.

The cracking chamber 36 described above may consist of any approved form of apparatus in which the oil may be supported in a body to permit the gas to pass countercurrent therethrough. The function of the cracking chamber is to provide a means by which the oil may be held at a cracking temperature for an extended period of time to permit the cracking and conversion reaction to take place. By means of the apparatus shown in the drawings, the oil is supported in comparatively thin bodies and the gas and vapors passing through the oil act to thoroughly agitate the oil so as to maintain a uniform temperature and to repeatedly bring the vapors into contact with the heated oil to assist in the heat reactions.

To effect the countercurrent treatment of the oil and vapors in the cracking chamber with the apparatus illustrated in the drawings, it is necessary to maintain a lower pressure in the cracking chamber from that in the separator in order that the oil may flow in a continuous circuit throughout the still. The oil entering the separator 62 preferably has a pressure of from 80 to 125 pounds per square inch and this pressure is reduced from 10 to 15 pounds in the cracking chamber. The amount by which the pressure is reduced, however, depends upon the difference in vertical head between the pipes 44 and 48 and is controlled to allow the oil to be admitted into the upper portion of the cracking chamber while the gas is being introduced at the bottom of the chamber. A ten to fifteen pound pressure differential will ordinarily produce an active circulation of the gases and vapors up through the body of the oil in the cracking chamber. To obtain this pressure differential, the oil flows through a float valve and is introduced into the cracking chamber under the pressure prevailing in the separator with only frictional losses. While the pressure of the gas and

vapors is reduced by means of a valve 47 in the pipe 48 (Fig. 1), the float valve 68 acts merely to maintain a predetermined level in the separator and only causes slight frictional losses in the pressure of the oil passing therethrough.

The pipe still 54 is shown more particularly in Fig. 1. The still consists of a series of pipes 128 which are connected to form a long continuous coil in which the oil is heated. The pipes are mounted in a horizontal position in a heating chamber 130 of a furnace 132 and the opposite ends of the pipe project through side walls of the furnace. The ends of the pipes 128 are connected by means of return bends, which are located on the outside of the walls to permit the return bends to be readily removed for cleaning and repairing the pipes. The pipe still is preferably heated by means of an oil or gaseous fuel, which is ignited in a combustion chamber 138 positioned outside of the heating chamber 130. The fuel is introduced into the combustion chamber 138 by means of a burner 140 and the products of combustion are deflected around an ignition arch 142 (Fig. 1) in passing to the upper portion of the heating chamber 130 through a flue 144. The products of combustion pass downwardly through the heating chamber 130 around the pipes 128 to a flue 146 and flow out to the atmosphere through a stack 148. By this arrangement, the heat is supplied to the pipe still coil in a direction countercurrent to the direction of movement of the oil therein, that is, the highest temperature is developed adjacent the outlet end of the heating coil and the lowest temperature developed adjacent the inlet end of the coil. In this way, the oil and gas are gradually heated up to the cracking temperature in passing through the pipe still.

With the apparatus outlined above, it will be seen that practically any desired combination of pressure and temperature may be maintained in the pipe still 54, separator 62, and cracking chamber 36. Temperatures of from 600-900° F. and pressures of from 60 to 125 pounds per square inch are the usual working temperatures and pressures which are employed in accordance with the end products desired. The form of pipe still shown in the drawings affords a means by which a large amount of heat may be rapidly placed in the oil and the separator and cracking chamber give a means by which a large body of oil may be maintained at a uniform temperature during the cracking operation. The separator and cracking chamber may be insulated as illustrated at 200 to prevent radiation losses and these parts may be heated in the usual manner by means of exhaust flue gases.

While it is preferred to introduce gas under pressure into the oil entering the pipe

still, to furnish a carrying medium for the oil vapors and to induce a positive, rapid, circulation of the oil and vapors, this addition of gas is not essential. Some gases are 5 always formed while cracking oil, and this gas, together with the vapors formed in the pipe still 54 and separator 62, will always produce an active countercurrent circulation of the oil and vapors in the cracking chamber 10 ber 36.

In the process outlined above, the gas introduced is still-head gas which is hydrocarbon that may enter into and assist in chemical reaction or cracking in the still. 15 For many purposes, natural gas is preferred to still-head gas because it contains more of the heavy hydrocarbons that may be useful in the formation of gasoline. Also, inert gases such as flue gas, air, etc., may be used 20 as an agitating and vapor-carrying medium, but it is preferred to use a hydrocarbon gas.

Having thus described the preferred form of the invention, what is claimed as new is:

1. A process of distilling oil comprising continuously circulating oil under pressure in a stream through a heater to raise it to a cracking temperature, passing the oil from the heater into an enlarged chamber and holding the oil under superatmospheric pressure 25 sure and at a cracking temperature for sufficient period of time to promote cracking reactions, subjecting the vapors from the chamber to reflux condensation and then final condensation and withdrawing concentrated residue oil from said chamber under a surging action by intermittently at frequent intervals withdrawing the residue under sudden reduction of pressure to control the concentration of the oil in the chamber. 30
2. A process of distilling oil comprising continuously circulating oil under pressure in a stream through a heater to raise it to a cracking temperature, passing the oil from the heater into an enlarged chamber maintaining the oil in the chamber under superatmospheric pressure and at cracking temperatures, holding the oil in the chamber for a sufficient period of time to promote cracking reactions, withdrawing and condensing vapors from the chamber, removing residue oil from the chamber by a surging action by intermittently and quickly withdrawing residue oil from the chamber to control the oil concentration therein, releasing the pressure 45 sure of the withdrawn oil to vaporize it and condensing vapors formed from the residue oil to recover oil suitable for recracking. 50
3. The process of cracking hydrocarbon oils, which comprises continuously passing hydrocarbon oil to be cracked through a heating zone, heating the oil in said zone to a cracking temperature, passing the heated oil while at a cracking temperature into an enlarged chamber in which a body of oil is 55 collected, maintaining the oil in said zone and chamber under a superatmospheric pressure, withdrawing oil from said chamber while in a highly heated condition into an externally unheated distilling chamber in which a lower pressure is maintained and in which a substantial proportion of said withdrawn oil is vaporized, said oil residuum withdrawal being carried out under a surging action by intermittently at frequent intervals withdrawing the oil residuum from 70 said enlarged chamber under a sudden reduction in pressure, and collecting a distillate from the vapors produced from the oil withdrawn into said distilling chamber. 75
4. The process of cracking hydrocarbon oils, which comprises heating the oil to be cracked to a cracking temperature while passing a continuous stream of the same through a heating zone, passing the heated oil while at a cracking temperature into a plurality of enlarged cracking zones where-in the oil is maintained under cracking conditions of temperature under a superatmospheric pressure, and withdrawing oil from each of said cracking zones while at a high 80 temperature with a surging action into a distilling zone of lower pressure in which no further heat is applied to the oil and in which substantial vaporization of the withdrawn oil occurs, by intermittently at frequent intervals withdrawing said oil under a sudden reduction of pressure, and collecting a distillate from the vapors produced from the oil withdrawn into said distilling zone. 85
5. The process of cracking hydrocarbon oils, which comprises continuously passing hydrocarbon oil to be cracked through a heating zone in which the oil is heated to a cracking temperature under a superatmospheric pressure, passing the heated oil while at a cracking temperature through a series of enlarged cracking zones in each of which a body of oil is collected, maintaining the oil in said cracking zones under a superatmospheric pressure, stratifying the oil in each enlarged zone to separate an oil residuum therein, alternately withdrawing oil residuum from said cracking zones while in a highly heated state into an externally unheated distilling chamber in which a lower pressure is maintained than that maintained on the oil in said cracking zones and in which substantial portions of said withdrawn oil residuum is vaporized, said oil residuum withdrawal being carried out with a surging action by intermittently withdrawing the oil residuum from each cracking zone with a rapid rush under a sudden reduction in pressure, and collecting a distillate suitable as a cracking stock from the vapors evolved from the oil residuum withdrawn into said distilling chamber. 95

In testimony whereof I affix my signature.

HENRY L. DOHERTY.
